CHILD'S HIGHCHAIR

Raimo Olavi Simula, Pori, Finland, assignor to Scanbergo,
Elli Heinonen, Farsta, Sweden

Filed Aug. 1, 1973, Ser. No. 384,584

Claims priority, application Sweden Feb. 1, 1973

Term of patent 14 years

Int. Cl. D6—06

U.S. Cl. D6—8

FIG. 1

FIG. 2

FIG. 3

FIG. 1 is a front perspective view of a child's highchair showing my design;

FIG. 2 is a rear elevational view thereof taken from the side opposite FIG. 1; and

FIG. 3 is a top plan view thereof.

The undersides of the seat and step are plain.

I claim:

The ornamental design for a child's highchair, as shown and described.
